UNITED STATES PATENT OFFICE.

GUY P. THURBER, OF PITTSBURG, PENNSYLVANIA.

TIME RELAY RECORDING-CLOCK AND SIGNAL MECHANISM.

No. 822,029.

Specification of Letters Patent.

Patented May 29, 1906.

Application filed May 11, 1905. Serial No. 259,921.

To all whom it may concern:

Be it known that I, GUY P. THURBER, a citizen of the United States of America, residing at Pittsburgh, in the county of Allegheny and State of Pennsylvania, have invented certain new and useful Improvements in Time Relay Recording-Clocks and Signal Mechanism, of which the following is a specification, reference being had therein to the accompanying drawings.

This invention relates to certain new and useful improvements in time relay recording mechanisms, and relates more particularly to a novel form of clock adapted to be used in the engineer's cab of a locomotive.

The invention has for its object to provide a novel form of clock for recording the action of valves, the number of signals which the engineer has received, and the time of day each signal took place.

My invention aims to provide a time relay recording-clock particularly applicable to automatic signal devices, such as illustrated and described in connection with my accompanying application filed under even date.

Briefly described, my recording mechanism is similar to that used by the ordinary and well-known type of watchmen's clock, the signals being sent through electromagnets or relays. In order to introduce an increment of time between the first signal and the time the brake shall be applied, I have devised a special attachment, which will be hereinafter more fully described and then specifically pointed out in the claims.

In the accompanying drawings I have illustrated by a diagrammatic view a signal system used in connection with a track block system, an electrically-actuated throttle-controlling valve, and an electrically-actuated air-valve adapted to operate air-brakes. This diagrammatic view is designated Figure 1, and Fig. 2 is a diagrammatic view of the time relay recording-clock employed in connection with the signal system illustrated in Fig. 1.

Referring to the accompanying drawings, I have illustrated the track as divided into blocks A, B, C, D, E, and F, and I have shown a train upon the block B with the truck 1 across the rails. This truck 1 short-circuits the battery 2, which releases relay 3 and breaks circuit 4, fed by the battery 5, at the point designated 6. The breaking of the circuit 4 weakens relay 7, thus opening circuit 8

at point 9, fed by battery 10, and weakens relays 11 and 12.

The armatures of the relays 11 and 12 are connected with insulated rails 13 and 14, said rails being broken from the main track by means of the insulated rail-joints 15 and 16, 17 and 18, and when the signal is transmitted to relays 11 and 12 the circuit was broken across the joints 16 and 18 at points designated 19 and 20. We will assume that the locomotive on the insulated trucks 21 and 22 passes from block E toward block D across the insulated joints 18 and 23. The relay 24, fed by the battery 25, is immediately short-circuited and opens the connection at point 26, which opens circuit and sends the signals back, the relay 12 having already dropped from the signal ahead, and the rail 14 immediately becomes insulated from the main track and breaks all electrical connections toward the rear of the train at the insulated joints 18 and 23. When this occurs, the circuit 27 in the locomotive fed by the battery 28 weakens relay 29 and drops armature 30, connected with circuit 31, fed by battery 32, and breaks said circuit, which immediately releases the core of solenoid 34, which opens air-valve 35, connected by pipe 36 to air-tank 37, and blows the whistle 38, which is located close to the engineer. When the armature 30 drops, it engages contact 39 and makes connection with battery 32 through circuits 40 to a time-recording clock 41, which is electrically connected with the system through binding-posts ψ , x , y , and z . We will assume that it requires ten seconds for the engineer to operate the valves or throttle, and then at the end of that time circuit 42, fed by battery 32, is broken, which releases solenoid 44 and opens air-valve 45, connected with air-pipe 46, fed by air-tank 37, which releases air-valve 47 and closes throttle 48. As soon as the throttle 48 is closed the valve in cylinder 47 is actuated to admit air into the cylinder 50 and open air-valve 51, connected by pipe 52 with the air-tank 37, onto a main air-pipe 53, which connects up with the air-brakes of the train.

Assuming that the track-circuit 27, fed by battery 28, is broken by a signal which releases relay 29, the armature 30 will drop and the circuit 31, fed by battery 32, is broken at the point designated 33 and immediately releases signal-valve 34. At the same time armature 30 has made contact at the point 110

designated 39, closing circuit 40 through binding-post *z* to relay-magnet 75, which records the time the signal was received, and also passes through magnet 76 to battery 32 via binding-post *x*. When the magnet 76 is energized, it immediately releases dog 77 and allows shaft 78, which is driven by a clock mechanism, to start in motion. The back of the dog 77 is so designed that it will engage the slot in the wheel 79 when opposite the same and stop the shaft within some stated period of time—for instance, ten seconds, as heretofore stated. At the time this shaft is stopped brush 80 strikes an insulated point on the wheel and breaks circuit 42, fed through binding-posts *w* and *y*, which immediately releases brake-valve 44 and sets the brakes. At the same time that the circuit is broken the insulated wheel 81 closes the circuit across the two brushes 82, thus energizing relay-magnet 83 and recording the time that the brakes were set. After the engineer has received the signal through the valve 34 he has ten seconds in which to push the button *m*, which short-circuits battery 28 through relay 29, and if circuit 27 was closed to its normal condition the armature 30 immediately closes circuit 42, connecting brake-valve 44 by means of a cross-connecting circuit 84 back through battery 32 by the way of contact 33. This arrangement of the circuits avoids the breaking of the circuit 42 through contact-brush 80 in the clock, and consequently not setting the brakes. In this manner the engineer can avoid the stopping of the train. At the same time no signal is recorded against him by the recording-magnet 83, since the brake-valve has not been operated.

From the above it will be seen that the clock 41 registers the number of signals given to the engineer, the time of day each signal took place, and the length of time each signal was indicated on the clock.

It will be seen from the above description that the operation of the train is entirely under the control of the engineer; but in case he neglects his duty it immediately takes his place and stops the train within a safe time.

I do not care to confine myself to the type of mechanism employed to revolve the main operating-shaft of the clock nor to the mechanism employed for recording the time, as I preferably use the conventional form of watchman's clock at present used.

What I claim, and desire to secure by Letters Patent, is—

1. In a time relay recording-clock, the combination with an electrically-actuated air-brake system, and a shaft driven by a clock mechanism, of wheels mounted upon said shaft, brushes engaging two of said wheels, a dog engaging one of said wheels, a relay operated by a track block-circuit and adapted to elevate said dog to permit of the

movement of its respective wheel, the breaking of said circuit releasing said dog and stopping said wheel at a predetermined time, and breaking electrical circuit through said brushes to set said air-brakes, substantially as described.

2. The combination with an air-brake system and a shaft driven by a clock mechanism, of means to lock said shaft from rotation, electrically-actuated means operated by a track block-circuit to release said shaft, means to automatically stop said shaft, and means carried by said shaft for breaking a circuit and thereby actuating devices to set said air-brakes.

3. In apparatus of the type described, the combination with an electrically-actuated air-brake, and a shaft driven by clock mechanism, of brushes, a relay operated by a track block-circuit and adapted to stop the rotation of said shaft at a predetermined time, an electrical circuit broken through said brushes, mechanism included in circuit with said brushes and adapted when the circuit through the brush is broken to set said air-brakes, substantially as described.

4. The combination with an air-brake system, and a drive-shaft normally held stationary, of circuit making and breaking devices carried by the shaft and electrically-actuated means adapted to set said air-brakes by the breaking of the circuits resulting from the rotation of said shaft, substantially as described.

5. A system of the class described comprising a driven shaft, a pivoted dog adapted to normally hold said shaft from rotation, a relay actuated by a block-circuit to release said dog, said dog being adapted to automatically stop the shaft after a predetermined amount of rotation, and electrical means mounted adjacent to said shaft to set air-brakes by the rotation of said shaft.

6. A system of the class described comprising a driven shaft normally held stationary, electrical means to release said shaft to automatically set air-brakes, and means operated by said shaft for recording the time when the air-brakes are set, substantially as described.

7. A system of the class described comprising a driven shaft normally held stationary, electrical means to release said shaft to automatically set air-brakes, and electrically-actuated means operated by the movement of said shaft for recording the time the brakes are set and means manually operated to release said air-brakes, substantially as described.

In testimony whereof I affix my signature in the presence of two witnesses.

GUY P. THURBER.
